COMBINED PHONOGRAPH TABLE AND RACK FOR RECORD ALBUMS OR THE LIKE

Michael Ross, New York, N. Y., assignor to Decca Records Inc., New York, N. Y., a corporation of New York

Application July 16, 1954, Serial No. 31,464

Term of patent 3½ years

(Cl. D33—14)

Fig. 2

Fig. 1 is a front perspective view of a combined phonograph table and rack for record albums or the like embodying my new design; and

Fig. 2 is an end elevational view thereof.

I claim:

The ornamental design for a combined phonograph table and rack for record albums or the like, as shown.
